TEMPERATURE RESPONSIVE DEVICE

Victor Weber, Greensburg, Pa., assignor to
 Robertshaw Thermostat Company, Young-
 wood, Pa., a corporation of Pennsylvania

Application November 2, 1943, Serial No. 508,735

12 Claims. (Cl. 200—140)

This invention relates to control apparatus and, more particularly, to snap-action mechanism for controlling temperature, pressure or other physical conditions.

An object of the invention is to insure regulation of the controlled operation by the control apparatus within a reasonable approximation of the control setting.

Another object of the invention is to lessen the probability of undesired or hazardous conditions being created by failure of normal switch-contact operation.

Another object of the invention is to secure a uniform differential throughout the range of control settings when normal operation is superseded by delayed control action.

Another object of the invention is to utilize structure in common for normal and delayed action of the control apparatus.

Other objects and advantages will become apparent from the following description taken in connection with the accompanying drawing, wherein:

Fig. 1 is a plan view of the apparatus;

Fig. 2 is a side elevation with portions of the housing of the apparatus broken away and showing the switch elements in one position;

Fig. 3 is a plan view, similar to Fig. 1, but with the housing cover removed;

Fig. 4 is a side elevation of the structure shown in Fig. 3 but with the switch elements in a position other than that shown in Fig. 2;

Fig. 5 is an end view of the apparatus; and

Fig. 6 is a partial section taken on the line 6—6 of Fig. 3.

Referring more particularly to the drawing, there is shown an L-shaped frame 10, to which is secured by the screws 12, a channel-shaped cover 14. The arrangement provides a housing having an open end within which a block 16 of insulating material is secured by means of the screws 18. The frame 10 is adapted to be fastened to a control panel (not shown) by means of the lugs 20 through which suitable securing means may project.

The cover 14 is provided with a centrally located boss 22 having an axial opening in which a bushing 24 is secured and provides support for a scale 26 of suitable graduations. Cooperating with the scale 26 is a pointer 28 carried on an adjusting screw 30 which is threaded in an axial opening in the bushing 24 and projects therethrough into the cover 14. The pointer 28 may be provided with spaced arcuate slots 32 through which project clamping screws 34 carried by a

plate 36 secured to the adjusting screw 30 immediately behind the pointer 28. Loosening of the screws 34 permits the pointer 28 to be rotated relative to the screw 30 for calibrating the control.

The projecting end of the adjusting screw 30 within the cover 14 engages the center stud of an expandible and contractible diaphragm 38 and serves to support and move the diaphragm. The interior of the diaphragm 38 is in communication with a capillary tube 40 which is partly coiled inside the boss 22 and extends therefrom exterior of the cover where it may be secured by the clamp 41. The tube communicates with a temperature sensitive bulb 42 and, as is customary in such devices, a contractible and expandible liquid is provided in the bulb and the capillary tube so that upon expansion of the liquid as a result of the heat to which the bulb is subjected the liquid will be forced through the tube into the expandible and contractible diaphragm thereby actuating it to a sufficient extent to operate the parts to be described.

A button 44 provided on the face of the diaphragm 38 opposite the stud abuts a depression 46 formed in a main actuating lever 48. This lever, which is generally of U-shaped conformation, is provided with a knife-edge 50 serving to connect the legs of the U-shape. The knife-edge 50 is seated in a knife-edged bearing 52 formed on a bracket 54 secured to the inner wall of the L-shaped frame 10. The base of the U-shaped actuating lever 48 is recessed at the center portion to provide a seat 55 for one end of a tension spring 56, the other end of which is hooked in an aperture formed in the center cross-bar 58 of an R-shaped control lever 60.

The two legs 62 and 64 of the control lever 60 are provided with knife edges 63 cooperating with knife-edged bearings 65 formed in a channel-shaped support 66 extending substantially parallel with the base of the frame 10. The support 66 carries projections 68 which are loosely mounted in the wall of the L-shaped frame 10 adjacent the base thereof and serve to retain the support in position at one end. The support 66 at the opposite end carries an adjusting screw 70 bearing against the base of the frame 10. Lateral displacement of the control lever 60 is prevented by a bracket 72 carried by the inner wall of the frame 10 and having arms 73 projecting on each side of the legs 62 and 64. It will be apparent that the screw 70 may be adjusted to raise or lower the support 66 and change the tension of the spring 56 as desired.

An inverted V-shaped take-up arm 74 is attached to the control lever 60 rearwardly thereof by means of forwardly projecting spaced lugs 76 suitably notched for engagement with oppositely disposed shoulders 78 formed on the legs 62 and 64 of the control lever 60. The take-up arm 74 is further provided with a hook 80 which extends around the underside of the top bar of the R-shaped control lever 60 at the central portion thereof. The hook 80 limits the movement of the take-up arm 74 with respect to the lever 60 and cooperates with the projections 76 to attach it thereto. In addition, a plunger 82 secured to the control lever 60 above the hook 80 extends loosely through the take-up arm 74 and is provided with a compression spring 84 which normally urges the take-up arm toward the control lever and permits relative movement therebetween.

The take-up arm 74 extends beyond the top bar of the R-shaped control lever 60 and carries a contact block 86 of insulating material mounted thereon for restricted pivotal movement in a horizontal plane. A pair of contact bridges 88 are secured one on each end of the contact block 86 for cooperation with contacts 90, 92, 94 and 96 mounted on the insulating block 16 and projecting exteriorly of the cover 14. It will be observed that in this embodiment the contacts 90, 92 and 96 respectively are provided with terminal connections including screws 88, while the contact 94 is adapted for permanent connection with a conductor 100. It will be apparent, however, that such arrangement can be modified as dictated by the circuit arrangement with which the control apparatus is used.

The structure so far described constitutes a snap-action mechanism by which the control lever 60 can effect contact operation. Thus, as the liquid in the bulb 42 and the capillary tube 40 expands in response to the temperatures prevailing at the point where the bulb is located, the diaphragm 38 will also expand and urge the free end of the main actuating lever 48 toward the knife-edge bearing 65 of the control lever 60. Due to the tension of the spring 56, the control lever 60 and its companion take-up arm 74 will be moved to the right, as viewed in Fig. 2, with a snap-action as the actuating lever 48 moves overcenter past a line between the respective bearings of the two levers. Such snap-action causes disengagement of the contact bridges 88 and the contacts 90-96 as will be apparent. The position of the levers under these conditions is shown in Fig. 4 wherein it will be apparent that the bias of the spring 56 causing engagement between the contact bridges and contacts 90-96 has been overcome by operation of the thermostat. This open contact position will continue until the diaphragm 38 starts to contract upon cooling of the bulb 42 whereupon a similar overcenter snap-action will occur, but in the opposite direction, to cause contact engagement as the control lever 60 resumes its normal position as shown in Fig. 2.

This invention is more particularly directed to providing sequential operation of a plurality of control devices of which the switching device previously described forms one part. To this end, additional contacts are provided for support by the insulating block 16 and located between the contacts 90-96 and the wall of the L-shaped frame 10. These additional contacts may be two in number and are designated 102 and 104, respectively. The conductor 100 connects contact 94 with contact 104 permanently, while contact 102 is similar to contacts 90, 92 and 96, in having

5 a terminal connection including a screw 88. As indicated diagrammatically in Fig. 3, contacts 90 and 96 may be connected to line wires 106 and 108, respectively, while contacts 92 and 102 are connected to the heating element 109.

10 Contacts 102 and 104 cooperate with a contact bridge 110 mounted on an insulating plate 112 which is carried by a flexible member 114 on one end of a secondary lever 116. The secondary lever extends between the arms 73 of the bracket 72 and is provided with lateral projections 118 pivotally mounted in the arms 73 and serving to support the secondary lever 116 and associated parts in position for pivotal movement to engage and disengage the contacts 102, 104 and contact bridge 110. A compression spring 120 is mounted between the secondary lever 116 and the inner wall of the frame 10 on the side of the pivotal mounting opposite the contact bridge 110, thus serving to bias the contact bridge out of engagement with the contacts 102 and 104.

15 In accordance with the principles of this invention, the secondary lever 116 is located in such position that it is beyond the range of the overcenter snap-action of the main actuating lever 48. Thus, the normal movement of the main actuating lever 48 to effect this snap-action can occur without affecting the position of the secondary lever 116 in either contact engaged or disengaged position. In order to provide for operation of the contacts 102, 104 and 110, by movement of the main actuating lever 48 beyond the range of the overcenter snap action, interengaging means on the main lever 48 and secondary lever 116 are provided.

20 Such inter-engaging means may take the form of a rocker 122 mounted on a pivot 123 on the depending portion of an angular arm 124 projecting from the bracket 72 immediately below and inwardly of one of the arms 73 thereof. The rocker 122 extends toward the main actuating lever 48 in position to be engaged thereby when further movement thereof beyond the range of the overcenter snap-action occurs. Preferably, 25 the rocker 122 has a ramp 126 formed thereon and the lever 48 is provided with a lateral projection 128 which will ride along the ramp 126 and serve to tilt the rocker 122 during the further movement of the lever 48.

30 As it is desired that contact bridge 110 normally engage contacts 102, 104 the bias of spring 120 is overcome by a latching arrangement now to be described. The underside of the ramp 126 is engaged by the free end of a U-shaped strip 35 of spring metal 130 which is secured to the channel-shaped support 66 and has its free end spaced therefrom. The opposite end of the rocker 122 is thus urged about the pivot 123 toward a projection 132 which is formed on a depressed portion 134 of the secondary lever 116. Latching engagement between the secondary lever 116 and the rocker 122 is secured by forming the end of the rocker adjacent the projection 132 with a notch 136 with which the projection 132 may engage. As shown in Fig. 6, the secondary lever 116 is in what may be termed the unlatched position, notch 136 disengaged from the projection 132. In this position, the spring 120 has biased the lever 116 from normal latched position so that contact bridge 110 thereon is separated from contacts 102 and 104. A button 138 is provided on the exterior of the cover 14 to reciprocate a pin 140 carried thereby and extending into operative engagement with the lever 116 when the button is depressed. The pin is normally

biased out of engagement with the lever 116 by a compression spring 142 between the button and cover. The pin 140 engages the lever 116 on the side opposite the depressed portion 134 and thus serves to pivot the lever against the bias of the lever spring 120.

In the operation of the control apparatus described it may be assumed that the first set of contacts comprising contact bridges 88 and contacts 90-96 are engaged and the second set of contacts comprising contact bridge 110 and the contacts 102-104 are also engaged. Such closed position of the first set of contacts is due to the biasing action of the spring 56 of the overcenter snap-action mechanism, while the similar contact position of the second set of contacts is due to operation of the latching device of lever 116. The pointer 28 is now set at the temperature it is desired for the control to operate.

The circuit for the heating element 109 which heats a fluid in thermal contact with the bulb 42 may be traced from the line wire 106, contacts 90-92, heating element 109, contacts 102-104, conductor 108, contacts 94-96, to line wire 103. As the temperature reaches approximately the level for which it is set, the diaphragm 38 will expand sufficiently to cause the overcenter snap-action previously described and move the control lever 68 to the right as viewed in Fig. 2 carrying the take-up arm 74 with it to the position shown in Fig. 4. The contact bridges 88 thereupon become disengaged from contacts 90, 92, 94 and 96, thus interrupting the flow of current from the power lines 106 and 108 to the heating element 109.

So long as the diaphragm 38 remains in the expanded position the current will be interrupted and the heating element 109 will be deenergized. Upon cooling down of the fluid at the bulb 42 the diaphragm 38 will contract permitting the lower end of the main actuating lever 48 to pass the pivot point in the other direction causing the control arm 68 and the take-up arm 74 to move to the left from the position of Fig. 4 to that of Fig. 2 to close the circuit. Such operation of opening and closing the first contacts 90-96 may continue intermittently without any movement occurring on the part of the secondary lever 116 so that the contact bridge 110 thereon remains in engagement with the contacts 102-104.

However, the contact bridges 88 may under some condition become welded or otherwise immovably fixed to the contacts 90-96 whereupon, regardless of actuation of the control lever 68, the current supply to the heating element would not be interrupted. In this contingency, the diaphragm would continue to expand, thus moving the main actuating lever 48 beyond the usual range of overcenter snap-action. Engagement of the projection 128 on the main actuating lever 48 with the ramp 126 of rocker 122 would then occur until projection 128 is caused to ride along the ramp 126 and depress the rocker 122. The bias of the spring strip 130 is overcome and the projection 132 slips off the rocker causing the secondary lever 116 to become unlatched. The bias of the spring 120 thereupon is sufficient to pivot the secondary lever 116 about the projections 118 thereon and the contact bridge 110 separates from the contacts 102-104 with a snap action to assume the position shown in Fig. 2.

As the circuit of the heating element 109 is now interrupted by disengagement of contact bridge 110 from contacts 102, 104 the heating

element 109 becomes deenergized, although the first contacts remain engaged due to the welding action described. Thus, the probability of undesired or hazardous conditions being created by failure of normal switch contact operation is lessened. The operation of the secondary lever 116 to disengage the second contacts renders the deenergization of the heating element permanent due to engagement of the projection 132 with rocker 122. Thus, although the diaphragm 38 contracts sufficiently to permit the main actuating lever 48 to return to biased position, the second contacts remain disengaged. Warning is thereby afforded of the inoperative condition of the first contacts and steps can be taken to remedy such condition.

In order to reengage the second contacts, the button 138 is moved inwardly to cause pin 140 to engage and move the lower end of the secondary lever 116, thus overcoming the bias of spring 120 and permitting spring arm 130 to tilt the rocker 122 and engage notch 136 with projection 132. Due to the resumed latching engagement, the secondary lever 116 will remain in contact position until the main actuating lever 48 again travels past the range of overcenter snap-action thereof and operates the rocker 122 as described.

It will be apparent that the delay period or differential between operation of the overcenter snap-action device and operation of the rocker 122 to release the secondary lever 116, may be made uniform throughout the range of control settings. That is, while the control is adjustable for normal operation at different temperatures, the delayed control action by the secondary lever will interrupt the circuit at a certain difference of temperature higher than that for which the control has been set. Thus, if the control is set for 150° operation, the secondary lever may interrupt the circuit at 190° or, if the setting is 200°, the interruption may occur at 240°, there being a 40° differential regardless of the initial temperature setting.

From the foregoing it will be apparent that the apparatus can regulate a controlled operation at the desired setting or at a predetermined differential beyond such setting. The specific embodiment herein described is for temperature regulation, but it will be apparent that other physical conditions may be controlled and various circuit arrangements utilized including separate circuits for the first and second contacts. The device is described and shown as a heat control but could be modified for cold control by rearrangement of the parts as will be apparent. Other modifications and changes may be made in the details of construction and arrangement of parts within the scope of the appended claims without departure from the spirit of the invention.

I claim:

1. A control apparatus comprising a first control device movable between controlling positions and being biased to one of said positions, means initially operable for causing movement of said device against its bias from one controlling position to another, a second control device movable between controlling positions by a subsequent operation of said means upon completion of said initial operation, condition responsive means associated with said operable means and having a range of action sufficient to cause sequential operation of said control devices thereby, and man-

ually operable means for resetting said second control device to its unoperated position.

2. A control apparatus comprising a first control device movable between controlling positions, means initially operable for causing movement of said device from one controlling position to another, a second control device movable between controlling positions, snap-action means associated with said second device and biasing it to one controlling position, means for holding said second device against its bias in another controlling position, said holding means being rendered ineffective for the purpose aforesaid by a subsequent operation of said operable means, condition responsive means associated with said operable means and having a range of action sufficient to cause sequential operation of said control devices thereby, and manually operable means for resetting said second device in the position where said holding means is effective.

3. A control apparatus comprising a first control device movable between controlling positions, snap-action means associated with said device and biasing it to one controlling position, said means being operable by overcenter action from biased position for causing movement of said device to another controlling position, a second control device movable between controlling positions, snap-action means associated with said second device and biasing it to one controlling position, means for holding said second device against its bias in another controlling position, said holding means being rendered ineffective for the purpose aforesaid by said first snap-action means after passing overcenter and condition responsive means associated with said first snap-action means and having a range of action sufficient to cause sequential operation of said control devices thereby.

4. A control apparatus comprising a first control device movable between controlling positions, means initially operable for causing movement of said device from one controlling position to another, a second control device movable between controlling positions, snap-action means associated with said second device and biasing it to one controlling position, latching means for holding said second device against its bias in another controlling position, said means including a rocker element positioned in fixed relation with said operable means for engagement thereby subsequent to said initial operation for releasing said second device to return to its biased position, condition responsive means associated with said operable means and having a range of action sufficient for said initial operation thereof and thereafter to cause said engagement with said rocker element, and means for adjusting said condition responsive means to different condition settings whereby said initial operation occurs under predetermined conditions with a uniform differential for said subsequent operation.

5. A sequential snap-action mechanism comprising in combination, a control device, a main actuating lever, a control lever for said device, a tension spring interconnecting said levers for overcenter snap-action of said main lever to actuate said device by said control lever, a pivoted lever spaced from said main lever, a coil spring exerting pressure tending to rotate said pivoted lever, and latching means engageable with said pivoted lever to prevent rotation thereof, said latching means including a portion engageable by said main lever beyond the range of overcenter action thereof.

6. A sequential snap-action mechanism comprising in combination, a control device, a main actuating lever, a control lever for said device, a tension spring interconnecting said levers for overcenter snap-action of said main lever to actuate said device by said control lever, a pivoted lever located beyond the range of said overcenter action, a coil spring exerting pressure tending to rotate said pivoted lever, a rocker member having one end adapted for latching engagement with said pivoted lever and another end projecting toward said main lever, yieldable means operative on said projecting end for urging said rocker into said latching engagement and thereby preventing rotation of said pivoted lever, and rocker operating means on said main lever adapted to overcome said yieldable means and release said latch upon movement of the main lever beyond said range of overcenter action.

7. In a snap-action mechanism, the combination with a main actuating lever, a control lever, and a tension spring interconnecting said levers for overcenter snap-action of said control lever upon movement of said main lever, of a secondary lever pivoted intermediate its ends and located beyond the range of said overcenter action, means for biasing said secondary lever to one position, manually operable means for actuating said lever against its bias to another controlling position, yieldable means engaging with said secondary lever and preventing its return to the first said position, and interengaging portions on said yieldable means and main lever for releasing said secondary lever by movement of said main lever.

8. A control apparatus comprising condition responsive means, a first control device to be actuated thereby, means for transmitting movement from said condition responsive means to said device including a main lever arranged to be actuated by said device, a control lever arranged to actuate said control device, oppositely disposed bearings for said levers, a tension spring interconnecting said levers for transmitting movement of the main lever to the control lever and imparting overcenter snap-action to the latter as it moves past a line between said bearings, a second control device, a secondary lever connected to said second device and pivoted intermediate its ends, said secondary lever being located beyond the range of said overcenter action, means for biasing said secondary lever to one controlling position, manually operable means for actuating said lever against its bias to another controlling position, yieldable means engaging with said secondary lever and preventing its return to the first said position, and interengaging portions on said yieldable means and main lever for releasing said secondary lever by movement of said main lever beyond said range of overcenter action.

9. A control apparatus comprising condition responsive means, a first control device to be actuated thereby between closed and open positions to control the condition to which said means is responsive, means for transmitting movement from said condition responsive means to said device including a main lever arranged to be actuated by said device, a control lever arranged to actuate said control device, oppositely disposed bearings for said levers, a tension spring interconnecting said levers for transmitting movement of the main lever to the control lever and imparting overcenter snap-action

to the latter as it moves past a line between said bearings, said first control device being biased by said spring to a closed position, a second control device also to be actuated by said condition responsive means between closed and open positions to control the said condition, a secondary lever yieldably connected to said second device and pivoted intermediate its ends, said secondary lever being located beyond the range of said overcenter action, means for biasing said secondary lever to a position in which said second device is in an open position, manually operable means for actuating said lever against its bias to a position in which said second device is in a closed position, yieldable means engaging with said secondary lever and preventing its return to the first said position, said secondary lever maintaining said second device closed irrespective of the open or closed position of said first device by operation of said main lever within said overcenter snap-action range, and interengaging portions on said yieldable means and main lever for releasing said secondary lever by movement of said main lever beyond said range of overcenter action whereby said second control device is actuated to open position and can control the said condition irrespective of whether said first control device remains in a closed position after said overcenter snap-action from biased position has occurred.

10. A control apparatus comprising a control device movable between controlling positions, thermally operable means for causing movement of said device from one controlling position to another, a second control device movable between controlling positions by a subsequent operation

5 of said means upon completion of said thermal operation, and latching means for holding said second device in one position until released by said thermally operable means in said subsequent operation.

15 11. A control apparatus comprising a control device movable between controlling positions, thermally operable means for causing movement of said device from one controlling position to another, a second control device movable between controlling positions by a subsequent operation of said means upon completion of said thermal operation, latching means for holding said second device in one position until released by said thermally operable means in said subsequent operation, and means for adjusting said thermally operable means for operation at different temperatures with uniform differential for said subsequent operation.

20 12. A control apparatus comprising in combination, a main actuating lever, a control lever, a tension spring interconnecting said levers, a pivoted lever spaced from the main lever, means tending to rotate said pivoted lever, latching means for preventing rotation of said pivoted lever, means operable upon movement of said main lever beyond a predetermined distance for releasing said latch, and condition responsive means for normally operating said main lever within said distance to cause operation of said control lever without releasing said latch, and being adapted under abnormal conditions for operating said main lever beyond said distance to release said latch.
